UNITED STATES PATENT OFFICE.

ELLERY POLLARD, OF BROOKLYN, NEW YORK.

BINDING APPLIANCE.

1,344,959.

Specification of Letters Patent. Patented June 29, 1920.

Application filed March 13, 1919. Serial No. 282,328.

To all whom it may concern:

Be it known that I, ELLERY POLLARD, a citizen of the United States, residing at the borough of Brooklyn, in the county of Kings 5 and State of New York, have invented a new and useful Improvement in Binding Appliances, of which the following is a specification.

This invention relates to releasable binding devices such for example as the tourniquet where the characteristic of quick application is a prime requisite, where security of the engaging means is necessary to maintain the given tension of the appliance, and 15 where disengagement can be conveniently effected.

In brief my invention consists of a flexible strand having a fixed stop and loosely carrying a ring which has a frictional inner 20 periphery, the strand being returned through said ring to encircle an object to be bound; the stop being characterized as having a surface, opposed to the ring, capable of co-acting therewith in such manner that when 25 the strand is drawn from its free end, to tighten the appliance about the object, the strand is caught between the stop and the ring, whose inner peripheral edge bites into the strand at that point and thus securely 30 holds it in a binding taut state. The binding device is however easily releasable simply by lifting the stop, which may have the form of a handle capable of being grasped between the finger and thumb, this 35 act having the effect of separating the stop from the ring and leaving the strand free to run through the ring.

Other features and advantages of my said 40 invention will hereinafter appear.

In the drawing:—

Figure 1 is a group of diagrams, representing the progressive stages in the operation of forming the stop knot.

Fig. 2 is a view of the appliance.

Fig. 3 is an enlarged, sectional view of a portion of the appliance, showing the stop knot, and the co-action therewith of the gripping ring.

Fig. 4 is an elevation, showing the appliance employed as a tourniquet, with the pad pressed against an artery in a human wrist, and

Fig. 5 is an end elevation of the same.

While serviceable for various purposes, I 55 have in this application illustrated my improved binding appliance in the form of a

tourniquet, whose use for first aid, to prevent loss of blood, must be efficient, capable of instantaneous employment, and always available. Therefore my improved appliance is so devised that it can be sold for a trifle and carried by all as a part of necessary pocket contents.

In the figures the device is seen to comprise a flexible strand 1, which may be a 60 piece of fish-line or whipcord, of fine quality, to be non-fraying and durable. Near one end of the strand, which is of suitable length, it is provided with a stop as 2, which may consist of a knot formed in the strand. 65 As an example of a desirable form of such knot, possessing the desired qualifications, it is produced as shown in the progressive diagrams of Fig. 1. Thus, as in diagram *a*, the strand is first doubled to form a loop. 70 Then, as in diagram *b*, the short end *a*¹ of the strand has been turned about the root of the loop to form a first coil *b*¹, while in diagram *c* said short end has been wound several times at the loop side of coil *b*¹ to 75 form the succeeding coils *c*¹. In diagram *d* the next stage shows the short end as passed through the loop, where it is to be grasped, while the long end of the strand is drawn upon to contract the loop upon the outer 80 surface of coils *c*¹, in which act the short end of the strand becomes caught between said loop and coils, as shown in diagram *e*, leaving a substantially flat surface at *e*¹ for the inner portion of the coils. The stop 2 is 85 thus constituted as an integral fabrication of the strand 1, and at its surface *e*¹ provides a seat for a ring or eyelet 3 that is threaded loosely upon said strand, the orifice in said ring or eyelet being large enough to receive 90 said strand in double ply. Thus, for service the stop 2 and the free end of the strand project at one side of the ring or eyelet, and a contractile and extensible loop 5 formed 95 from the strand extends at the other side of the loop. The ring or eyelet 3 is given a frictional inner edge, which may be created by leaving a bur at the side of said ring or eyelet opposed to the seat *e*¹ on stop 2, whereby the free portion of the strand, while 100 capable of drawing easily through the ring or eyelet to tighten the appliance upon an object which it is to bind, may be retarded against withdrawal.

It is however not alone due to this frictional character of the inner peripheral edge of the ring or eyelet that the appliance 110

becomes locked in its binding relation to an object, this effect being achieved instead through the correlated efforts of several factors. In applying the device to bind an object, as 6, the loop 5 is placed thereover and then the free end of the strand is drawn through the ring or eyelet until said loop 5 tautly binds upon said object. This taut binding causes the surface of the object to 10 press outwardly upon the strand, which urges the ring or eyelet to press a portion of the strand between it and the seat e^1 , whereby the frictional or burred inner edge of the ring or eyelet bites into that portion of the strand, the grip thus effected becoming the 15 more secure according to the degree of tension created by the tautness of the binding action. It will also be appreciated that the flexible character of the cord used for the strand 1, and of which material the seat e^1 is composed, assists, by co-action with the ring or eyelet, through the embedment thus offered, in increasing the efficiency of the gripping factors.

25 For tourniquet practice a pad member, as 7, may be carried by the strand within the loop portion 5 thereof, in order that said member may be placed upon an artery to exert pressure thereon in stopping the flow 30 of blood. Or, obviously, any other desirable form of pad, either connected with or separate from the appliance, may be employed in conjunction therewith.

In some cases the appliance may be used 35 without a pad, as for instance where it is employed simply as a securing band or girdle.

I claim:—

40 1. A binding appliance consisting of a flexible strand, a fixed stop thereon, and a flat ring to receive said strand, doubled, with said strand forming a contractible loop, said stop having a substantially flat surface to co-act with said ring in gripping 45 the strand as tightened about an object, to secure the appliance against loosening.

2. A binding appliance comprising a flexible strand having a knot formed near one end thereof, and a flat ring loosely fitted on said strand, said ring adapted to 50 also receive a double ply of said strand in the formation of a girdling loop, and the inner surface of said knot, opposed to said ring, having a substantially flat formation for the purpose of frictionally gripping 55 said strand between said knot and ring when the loop is tightened about an engirdled object.

3. A binding appliance comprising a flexible strand having a knot formed near 60 one end thereof, the inner surface of said knot being of substantially flat formation, and a flat ring slidable on said strand, doubled, leaving a contractible loop in the strand, the inner peripheral edge of said ring having one-way acting frictional engaging means which co-act with the opposed surfaces of said knot and ring to effect 65 a frictional grip of said strand when the loop is tightened about an engirdled object, 70 while permitting the free passage of said strand in its loop contracting movement.

4. A tourniquet comprising a flexible strand, doubled, a flat ring to receive the doubled ply of said strand, leaving a contractible loop, a pad carried by said loop, and a knot near one end of said strand, said knot having a substantially flat engaging surface to co-act with said ring in gripping 75 the manipulable portion of said strand, 80 when drawn tautly about an object, and said knot also serving as a releasing member.

In testimony whereof, I have signed my name to this specification in the presence of 85 two subscribing witnesses, this 7th day of March, 1919.

ELLERY POLLARD.
